United States Patent Office

Des. 223,597

Patented May 9, 1972

223,597

FABRIC BRUSH

Kurt Krusche, Frankfurt, and Hubert Zimmermann, Mannheim, Germany, assignors* to ALLSTAR Verbrauchsguter GmbH & Co. KG (Allstar Consumer Products Co.), Frankfurt, Germany

Filed Nov. 10, 1969, Ser. No. 19,995

Term of patent 14 years

Int. Cl. D4—02

U.S. Cl. D86—13

FIG. 1 is a front elevational view of a fabric brush showing our new design;

FIG. 2 is a right side elevational view of a fabric brush showing our new design, the left side elevational view being substantially a mirror image thereof; and

FIG. 3 is a top plan view of a fabric brush showing our new design.

We claim:

The ornamental design for a fabric brush, substantially as shown and described.
